FLUID PRESSURE REGULATING APPARATUS

Finn H. Gulliksen, Wilkinsburg, Pa., assignor to
Westinghouse Electric & Manufacturing Com-
pany, East Pittsburgh, Pa., a corporation of
Pennsylvania

Application October 21, 1936, Serial No. 106,797

4 Claims. (Cl. 172—239)

My invention relates to electric discharge apparatus and it has particular relation to apparatus for regulating the pressure of a fluid.

It is an object of my invention to provide a simple, inexpensive and tractable system for controlling the flow of a fluid in such manner that the pressure thereof is maintained at a predetermined value.

Another object of my invention is to provide highly sensitive apparatus which shall respond to a deviation in the pressure of a fluid from a given value to compensate for the deviation.

An incidental object of my invention is to provide apparatus for detecting and amplifying the effect of minute motions of a body such as a diaphragm, for example.

More specifically stated, it is an object of my invention to provide apparatus for detecting deviations in pressure of a fluid from a given value and for transmitting impulses to a compensating device to correct for the deviations.

According to my invention, I provide an electrical network including a pair of inductance coils, each of which is provided with a magnetic core. The coils are so connected in the network that their reactances counteract each other to normally balance the network. An armature of magnetic material is associated with the cores in such manner that its movement varies the reactance of the coils. The armature is mechanically connected to respond to the variations in pressure of the fluid.

When the pressure of the fluid deviates from a predetermined value, the armature moves unbalancing the network and producing electric current impulses dependent on the motion. The current impulses are amplified and transmitted to a magnetic system similar in its structure to the inductance coil arrangement. The armature of the latter system is connected to a valve which controls the flow of the fluid.

The novel features that I consider characteristic of my invention are set forth with particularity in the appended claims. The invention itself, however, both as to its organization and its method of operation, together with additional objects and advantages thereof will best be understood from the following description of a specific embodiment, when read in connection with the accompanying drawing, in which the single figure is a diagrammatic view showing an embodiment of my invention.

The apparatus shown in the drawing comprises a chamber 1 to which the fluid is supplied through a suitable tube 3. On one face the

chamber 1 carries a resiliently suspended diaphragm 5 from which a rod 7 projects. At the end of the rod 7 a lever 9 is pivoted and the lever, in turn, carries an armature member 11 pivotally supported at its lower end 13. When the pressure in the chamber 1 is at the desired value, the end of the rod 7 at which the lever 9 is pivoted is fixed and the armature 11 is in a fixed position. As the pressure varies in one sense or the other, the rod 7 is moved outwardly or inwardly displacing the armature member.

The armature 11 is located between a pair of core members 15 and 17 of C section that are so disposed that their legs 19 are opposite to each other. A coil 21 is wound on the connecting member 23 of each core 15 and 17. The coils 20 and 21 are connected to each other at one terminal and the remaining terminals are connected to the terminal taps 24 of the secondary 25 of a transformer 27, the primary 29 of which is supplied from a suitable alternating source. The secondary 25 is also provided with an intermediate tap 31 located substantially at its electrical center and between the intermediate tap and the junction point 33 of the coils 20 and 21, the primary 35 of a second transformer 37 is connected.

Preferably the cores 15 and 17 and the inductance coils 20 and 21 are of substantially identical structure and the armature 11 is disposed centrally between the cores so that normally the circuit including the secondary 25 of the supply transformer 27 and the coils 20 and 21 is substantially balanced and the potential impressed across the primary 35 of the transformer 37 is substantially zero. The movement of the armature 11 in response to a movement of the diaphragm 5 produces an increase in the inductance of one coil, say 20, and a decrease in the inductance of the other, 21, and this, in turn, results in the appearance of an alternating potential at the terminals of the primary 35 of the transformer 37.

The secondary 39 of the transformer 37 is connected between the control electrodes 41 of a plurality of discharge devices 43 and 45. Each of the discharge devices is provided with an anode 47 and a cathode 49, in addition to the control electrode 41. The discharge devices 43 and 45 are preferably of the high vacuum hot cathode type although gaseous hot cathode or even gaseous cold cathode discharge devices may be utilized.

Power is supplied to the discharge devices 43 and 45 from a transformer 51, the primary 53 of which is energized from the same source as

the transformer 27. The cathodes 49 of the discharge devices 45 and 47 are supplied with heating current from the same secondary section 55 of the transformer 51 and are, therefore, at substantially the same potential. The anode 47 of one discharge device 45 is connected to the anode 47 of the other discharge device through a plurality of resistors 57, 59 and 61 which are symmetrically connected. The centrally connected resistor 59 is provided with a movable intermediate tap 63.

To impress potentials between the anodes 47 and the cathodes 49 of the discharge devices 43 and 45, the upper terminal 65 of a secondary section 67 of transformer 51 is connected to the movable tap 63 of resistor 59 while the lower terminal 67 of the section is connected to the center tap 71 of the secondary section 55. The resistor tap 63 is normally maintained at a central point intermediate the anodes 47 and is adjusted to compensate for differences in the discharge devices 43 and 45. Capacitors 73 and 75 are connected in each case between the anode 47 and the tap 63 to filter out any alternating current ripples.

Under normal circumstances, the instantaneous value of the potential impressed by the transformer 51 between the tap 63 and the cathode 49 of one discharge device 43, say, is substantially the same as the instantaneous potential impressed between the tap and the cathode of the other discharge device 45. When the armature 11 is in the central position, the potential impressed between the control electrodes 41 of the discharge devices is substantially zero and the current transmitted through the discharge devices 43 and through the portion of the resistor 59 connected to its anode 47 and the resistor 57 is substantially the same as the current transmitted through discharge device 45, the remaining portion of resistor 59 and resistor 61. The anodes 47 of the two discharge devices are therefore at substantially the same potential. However, when the armature 11 moves in one direction or the other, a potential is impressed at the terminals of the secondary 39 of the transformer 37. This potential is impressed between the control electrodes 41 and, depending upon the direction of motion of the armature 11, the potential of the control electrode 41 of one of the discharge devices is positive relative to its cathode 49, while the potential of the control electrode of the other is negative relative to its control electrode at the time when the anode cathode potential impressed on the discharge devices is positive. In such a case, greater current flows through the former discharge devices than through the latter and the difference of potential between the tap 63 and the anode 47 of the first discharge device is greater than the potential difference between the tap 63 and the anode of the second discharge device. The anodes 47 are, therefore, at different potentials.

To further amplify the effect attained, an additional pair of discharge devices 77 and 79 are provided. The discharge devices 77 and 79 are connected precisely in the same manner as the pair just discussed. The control electrodes 81 of the last-mentioned discharge devices 77 and 79 are connected each to an anode 47 of the first-mentioned discharge devices 43 and 45. Accordingly, when the armature 11 is moved from its equilibrium position a difference of potential is impressed between the control electrodes 81 of the last-mentioned discharge devices 77 and 79

and a difference of potential exists between their anodes 83.

The difference of potential thus derived from the movement of the armature 11 is impressed between a pair of conductors 85 and 87. To convert this difference of potential into a compensating effect, a motion receiving system similar to the motion transmitting system discussed above, is provided.

The motion receiving system comprises a pair of coils 88 and 89 each of which is connected between the conductors 85 and 87, through half wave rectifiers 91 and 93. The rectifiers 91 and 93 may be ordinary dry rectifiers of the copper-copper-oxide type and they are so connected to the coils 88 that current of one polarity is permitted to pass through one coil 88 and current of the opposite polarity is restrained while current of the last-mentioned polarity is permitted to pass through the other coil 89 and current of the first-mentioned polarity is restrained. The inductance coils 88 and 89 are each provided with cores 95 and 97 of the same structure as those associated with the diaphragm 5 and, in addition, an armature 99 is disposed between the cores in the same manner as the transmitting armature 11 is disposed between its associated cores 15 and 17.

When a potential of one polarity or the other is impressed between the conductors 85 and 87, current flows through one coil 88 or the other 89, magnetizing the associated core 95 or 97 and causing the armature 99 to move in one direction or the other. The armature 99 is pivotally supported at one end 101 and at the other end carries a lever 103 which, in turn, is coupled through a spring 105 to a resiliently supported jet pipe 107. As the armature 99 moves, the pipe 107 is pivoted and the flow of fluid is so varied as to compensate for the deviations in pressure.

Although I have shown and described a certain specific embodiment of my invention, I am fully aware that many modifications thereof are possible. My invention, therefore, is not to be restricted except insofar as is necessitated by the prior art and by the spirit of the appended claims.

I claim as my invention:

1. In combination, a transmitting network having a pair of coils, core means associated with each coil and armature means associated with said core means, said core and armature means being so disposed relative to each other that the movement of said armature means in one sense produces an increase in the reactance of one coil and a decrease in the reactance of the other coil and a movement of said armature in the opposite sense produces an increase in the reactance of said last-mentioned coil and a decrease in the reactance of said first-mentioned coil, a pair of terminals, means for producing a difference of potential between said terminal in response to a variation of the reactance of said coils, the polarity of said difference of potential depending on the sense of the movement of said armature means, an additional pair of coils, additional core means associated with each said additional coil and additional armature means associated with said additional core means, said additional core and armature means being so disposed relative to each other that current flow in one of said additional coils produces movement of said additional armature means in one sense and current flow in the other of said additional coil produces movement of said additional armature means in the opposite sense and means for connecting each

of said additional coils across said terminals, said connecting means including means for restraining the passage of current of one polarity through one of said additional coils and for restraining the passage of current of the opposite polarity through the other of said additional coils.

2. In combination, a source of periodic current having a pair of terminal taps and an intermediate tap, a pair of coils connected in series with each other and to the terminals of the source, core means associated with each coil and armature means associated with said core means, said core and armature means being so disposed that the movement of said armature means in one direction causes an increase in the reactance of one of said coils and a decrease in the reactance of the other of said coils and movement of said armature means in the opposite direction causes an increase in the reactance of said last-mentioned coil and decrease in the reactance of said first-mentioned coil and output circuit means connected between said intermediate tap and said junction point of said coils.

3. In combination, a source of periodic current having a pair of terminal taps and an intermediate tap, a pair of coils connected in series with each other and to the terminals of the source, core means associated with each coil and armature means associated with said core means, said core and armature means being so disposed that the movement of said armature means in one direction causes an increase in the reactance of one of said coils and a decrease in the reactance of the other of said coils and movement of said armature means in the opposite direction causes an increase in the reactance of said last-mentioned coil and decrease in the reactance of said first-mentioned coil and output circuit means connected between said intermediate tap and said junction point of said coils, said output circuit means comprising a pair of current paths each of which includes in effect a discharge path having an anode, a cathode

and a control electrode, means for impressing a potential derived from said source between the anodes and the cathodes of the discharge paths and means for impressing between the control electrodes of the discharge paths a potential dependent in polarity on the direction of movement of said armature.

4. In combination, a transmitting electrical network having a pair of electrical coils, magnetic core means associated with each coil and magnetic armature means associated with said core means, said core and armature means being so disposed relative to each other that the movement of said armature means in one sense produces an increase in the reactance of one coil and a decrease in the reactance of the other coil and a movement of said armature in the opposite sense produces an increase in the reactance of said last-mentioned coil and a decrease in the reactance of said first-mentioned coil, a receiving electrical network including a pair of electrical coils, magnetic core means associated with each coil and armature means associated with said core means, said core and armature means being so disposed relative to each other that current flow in one coil produces movement of said armature means in one sense and current flow in the other coil produces movement of said armature means in the opposite sense and means responsive to the variations of the impedance of the coils in said transmitting network for causing current to flow in said receiving network, said last named means including a plurality of electric discharge devices each having a plurality of principal electrodes and a control electrode, means for impressing potential between the said principal electrodes and means including the coils of said transmitting network for impressing potential on the control electrodes of said discharge devices.

FINN H. GULLIKSEN.
